COMBINED TRY-MITRE SQUARE AND ANGLE FINDER

Donald L. Payne, Rockford, Ill., assignor to Pro Products, Incorporated, Rockford, Ill.

Filed Feb. 26, 1973, Ser. No. 335,892

Term of patent 14 years

Int. Cl. D10—04
U.S. Cl. D52—6 A

FIG. 1 is a front elevational view of a combined try-mitre square and angle finder showing my new design;
FIG. 2 is a top plan view thereof;
FIG. 3 is a bottom plan view thereof;
FIG. 4 is a rear elevational view thereof;
FIG. 5 is a left side elevational view thereof;
FIG. 6 is a right side elevational view thereof.

I claim:

The ornamental design for a combined try-mitre square and angle finder, as shown.
